UNITED STATES PATENT OFFICE.

GRACE D. HARPER, OF MINNEAPOLIS, MINNESOTA.

DESIGN FOR A COMB.

48,972.

Specification for Design.

Patented May 2, 1916.

Application filed May 24, 1915. Serial No. 30,232. Term of patent 7 years.

To all whom it may concern:

Be it known that I, GRACE D. HARPER, a citizen of the United States, residing in the city of Minneapolis, county of Hennepin, and State of Minnesota, have invented a new, original, and ornamental Design for Combs, of which the following is a specification, reference being had to the accompanying drawing, forming part thereof.

Figure 1 is a side elevation of a comb,

showing my new design; Fig. 2 is a fragmentary plan view thereof; and Fig. 3 is an end view of the same.

I claim:

The ornamental design for a comb, as shown.

GRACE D. HARPER.

Witnesses:

F. C. CASWELL,

A. M. RUGE.
